EXTENSIBLE FRAME FOR A MOBILE IRRIGATION DEVICE

David Kane, 5036 Roosevelt Ave.,
San Antonio, Tex. 78214

Filed Dec. 1, 1966, Ser. No. 4,873

Term of patent 14 years

(Cl. D40—1)

FIGURE 1 is an isometric view of the extensible frame for a mobile irrigation device showing my new design in a partially extended condition;

FIGURE 2 is a side elevational view thereof in a fully retracted condition, the dot-dash showing being for illustrative purposes only; and

FIGURE 3 is an isometric view thereof showing it in a fully extended condition.

This application is a continuation-in-part of my application Ser. No. D-87,217 filed Sept. 29, 1965 and now abandoned.

I claim:

The ornamental design for an extensible frame for a mobile irrigation device, substantially as shown and described.
